UNITED STATES PATENT OFFICE.

WILLIAM HEIB, OF PHILADELPHIA, PENNSYLVANIA.

DESIGN FOR A GUTTER-HANGER.

SPECIFICATION forming part of Design No. 31,508, dated September 12, 1899.

Application filed August 21, 1899. Serial No. 728,018. Term of patent 7 years.

To all whom it may concern:

Be it known that I, WILLIAM HEIB, a citizen of the United States, residing at Philadelphia, in the county of Philadelphia and 5 State of Pennsylvania, have invented and produced a new and original Design for Gutter-Hangers, of which the following is a specification, reference being had to the accompanying drawings, forming part thereof.

Figure 1 is a perspective view of a gutter-hanger, showing my new design; and Fig. 2 is 10 a longitudinal central sectional view thereof.

As shown in the drawings, the leading or material feature of my design consists of a 15 channel-bar A, bent to a curve substantially as shown. The flanges B of the channel are upon the periphery of the curve and are

turned outward at one end of the curve to form the eyes C, while the web or central section of the channel is turned inward to form 20 the tongue D.

Having described my invention, what I claim as new, and desire to secure by Letters Patent, is—

The design for a gutter-hanger, substantially as shown and described. 25

In testimony whereof I have signed my name to this specification in the presence of two subscribing witnesses.

WILLIAM HEIB.

Witnesses:

THOMAS S. GATES,
C. N. BUTLER.
